United States Patent Office.

JOHN H. PUTMAN, OF GLOVERSVILLE, NEW YORK.

Letters Patent No. 101,506, dated April 5, 1870.

IMPROVEMENT IN GLOVES.

The Schedule referred to in these Letters Patent and making part of the same.

To whom it may concern:

Be it known that I, JOHN H. PUTMAN, of Gloversville, in the county of Fulton, in the State of New York, have invented certain Improvements in Gloves, of which the following is a specification.

In the drawings—

Figure 1 is a perspective of a glove, showing the inside of the hand and the inside of the thumb-piece and fingers;

Figure 2, an outline of the inside or palm-piece of the glove, and the thumb-piece and fingers in one piece;

Figure 3, an outline of the back of the glove, the thumb-piece that covers the back of the thumb and backs of the fingers;

Figure 4, an outline of the piece that forms the sides of the fingers, technically called "fourchette;" and

Figure 5 is a section of the back of the thumb in perspective.

In the manufacture of gloves, it is an object to have as few seams therein as possible, which necessitates the cutting the glove from the skin of which it is made in as few pieces, in such shape as will fit the hand, without waste of material, and so as to have the few seams so located that the greatest amount of wear will not come upon them.

Gloves have been cut having the inside of the thumb on the piece that forms the inside of the hand part of the glove, but such gloves have had the thumb-pieces cut narrow at their bases, bringing the seams in such position as to receive most of the wear, and make a bad fit on the hand, and to obviate such difficulties is the object of this invention; and

It consists in the form or shape of the pieces from which the glove is made.

A represents the piece cut to form the back of the hand.

A', the back of the thumb, and having an angular projecting piece or gusset, a, on its side.

b b', the backs of the fingers.

B, the piece that forms the inside or palm of the glove.

B', the inside of the thumb, and cut from the same piece, and has an angular projection or gusset, a', on its side.

b' b'', the inside of the fingers.

c, the piece that forms the sides between the fingers.

In putting these pieces or parts that are shown in figs. 2 and 3 together, the point of the angular projection or gusset piece a on the outside part A is placed at the terminal point of slit that severs the inside part of the thumb from the inside or palm-piece at e, and the point of the angular projection or gusset a', on the inside of the thumb-piece B', will come to the end of the slit that severs the back of the thumb from the hand parts at d, when the parts are sewed together in the usual way.

A glove made from the pieces thus formed will give to the inside of the thumb-piece a wide base, as the gussets a and a' throw the seams farther apart than is usual, and at the same time give ample room for the thumb to enter, will fit easy upon the thumb and hand, and there is no seam where the wear is the greatest at the base of the thumb.

Nor is there any seam on the top or back of the thumb, as that part at the back of the glove A which forms the wrist is wide, and comes far enough to throw the seam into the center of the inside of the wrist, and where it will not in the least interfere with the different positions of the hand and thumb, the thumb being free to work in any direction.

This method of cutting gloves is applicable to the cutting out of mittens, as what is herein described as the invention only relates to that part of a glove by which the thumb-piece is connected to the inside and back of the glove, and will answer for mittens as well without departing from my invention.

Having thus described my invention,

What I claim, and desire to secure by Letters Patent, is—

1. The backs and inside pieces of gloves A B formed in such manner as that the back part A shall have the back of the thumb A' with the projecting gusset a and backs of the fingers b in one piece, and the inside part B shall have the inside of the thumb B' and the projecting gusset a' and the inside of the fingers b' in another piece, substantially as described.

2. The glove above described, as a new article of manufacture, when made of the parts A, B, and c, in the manner substantially as described.

JOHN H. PUTMAN.
